VAPORIZING MANIFOLD TYPE LIQUID FUEL BURNER

Alphonso A. Topp, Indianapolis, Ind.

Application August 5, 1947, Serial No. 766,185

4 Claims. (Cl. 158—91)

1

This invention relates to a vaporizing manifold type of fluid fuel burner which may be used with solid fuel when desired or required.

The chief object of the present invention is to provide a burner of the vaporizing type insofar as liquid fuel is concerned and one that is extremely simple and one wherein the normal fuel level is such that the fuel is subject to burner suction supply for transference to a vaporizing zone.

The chief feature of the present invention resides in the turbulence creating high velocity air supplies to the fuel outlet for suction supply and atomization of the fuel, the atomized fuel then being vaporized and burned.

Another feature of the invention resides in the manifold independent cap type plug for fuel and air deflection purposes and the multiple surface cleaning projections on successive stepped portions of the cap.

A further feature of the invention resides in the exterior radial ribbing of the central raised portion of the burner bowl or base.

Other objects and features of the invention will be set forth more fully hereinafter.

The full nature of the invention will be understood from the accompanying drawings and the following description and claims:

In the drawings—

Fig. 1 is a top plan view of a circular embodiment of the invention, a portion of the manifold being broken away to show the same in section.

Fig. 2 is a vertical sectional view taken on broken line 2—2 of Fig. 1 and in the direction of the arrows.

Fig. 3 is a perspective view of the cap type stepped plug and cleaner.

In Figs. 1 and 2 of the drawings there is illustrated a shallow bowl or base 10 having the outer rim 11, the downwardly directed supporting flange 12 and herein four arcuately and equally spaced air ports 13.

Defining same and extending upwardly therefrom are the tubular portions 14, the upper ends of which herein are coplanar with the upper edge of the rim 11. Disposed centrally within the bowl is the raised portion 15. Same exteriorly may be provided peripherally with radially directed fins 16 which, however, terminate short of the tubular portions 14.

The central portion 15 has its upper edge 17 also coplanar with the portions 14 and the rim 11. This central portion has coaxial opening or passage 18 therethrough which is threaded at 19 to take a fluid fuel supply pipe 20. The line des-

2

gnated FL in Fig. 2 designates the approximate level of liquid fuel in supply passage 18 and same is maintained by a float valve or other mechanism not shown and conventional to oil burner systems.

In Fig. 3 the cap type stepped plug is illustrated. It comprises a tapered or frusto-polygonal end 21 of a length that the face 22 is submerged in a liquid fuel supply system including

10 the invention. The opposite end includes a cap 23 that serves at its face 24 as an air diverter preventing direct air pressure discharge into fuel supply passageway 18. Between the cap and portion 21 is a step arrangement. Same herein 15 comprises lug portions 25 having lower faces 26.

The edges 21^a of portion 21 may serve as passageway cleaners and the spacers 25 also serve as cleaners for face 17 should carbon, etc., gradually accumulate. Liquid fuel can be sucked out 20 of passageway 18 through the spaces between the latter and portion 21. This passes laterally between cap 23 and face 17. Of course, if the fuel be gaseous it will flow from the passageway without the necessity of a suction lift.

25 Reference will now be had to the manifold shown in Figs. 1 and 2. Same comprises a central hub portion 27 having a downwardly opening air discharge opening 28 of an area to nest the cap 23 of said gravity seatable plug, the weight thereof being sufficient to seat said plug as described. The plug thus is independent of the manifold. Different size plugs accordingly may be selectively associated with the same base or bowl and manifold.

30 The manifold includes generally radially directed tubular portions corresponding in number to tubular portions 14. Each terminates in a downwardly directed portion 29 that is nested in tubular portion 14, the free end 30 resting on collar portion 31.

35 The curved portion 32 gradually constricts and the radial portion 33 further constricts the passage. The result, as herein disclosed, is that port 13 has an area about four times the discharge 40 outlet 34 of the radial tube. The direction of discharge into the hub is substantially tangential. Thus the air is swirling in the hub and discharges in a swirling column effect about the cap 23 into the bowl and about the central raised portion 45 thereof.

45 Such discharge creates a suction on the mouth of the fuel supply system that is between the cap and face 17. When liquid fuel is utilized it at this point is fully atomized and immediately 50 mixed with air so that a vapor mixture is created.

When ignited this mixture burns immediately adjacent the fuel discharge.

Such combustion obviously heats fins 16, tubular portions 14, 29, 32 and 33 as well as manifold 27. The result is the fuel is slightly pre-heated to expand it whether it be liquid or gaseous. The air entering ports 13 is also progressively heated so that the velocity is increased over and above that resulting from constriction. As a result the air discharged applies suction to 10 the fuel outlet of the system whether that fuel be liquid or gas.

The products of combustion flow outwardly and upwardly for heating purposes and the stack draft for the household type should be about fifteen (15) inches. The six-inch burner is adapted for tank heaters, the eight, ten and twelve inch burners are adapted for house heating purposes while larger sizes such as eighteen, twenty-four, thirty and thirty-six inch burners 20 are adapted for steam and hot water boilers.

It has been determined that a burner of this type utilizes approximately 90 percent air and ten percent fuel by volume. With gaseous fuel the air to fuel ratio is about four to one. Otherwise expressed, the six-inch size uses about two gallons of oil per day; the eight inch, two and a half gallons; the ten inch, four and a half to five gallons; and the twelve inch, six gallons per day. The latter will satisfactorily heat a 25 seven or eight room house, the ten inch a five room house, and an eight inch burner will heat a three or four room house.

Whenever the fuel supply situation prevents the use of gas or oil, the householder need only 30 open the furnace door and lift out the manifold. After supplying solid fuel and igniting same the bowl serves as a grate for such fuel, air thereto then being supplied by ports 13. In this use the plug shown in Fig. 3 preferably is utilized to 35 prevent clogging of passageway 18. Obviously the gas or liquid fuel supply to line 20 will be cut off.

Following solid fuel use the bowl is cleaned out, the manifold restored, the fluid fuel again 40 supplied and ignited whereupon the unit operates as originally intended.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In an oil burner the combination of a bowl 60 type base having an upwardly directed, fuel sup-

plying, apertured portion centrally disposed therein and an outwardly and upwardly directed rim, said rim and portion forming a channel about the latter, a plurality of upwardly directed tubes disposed in the channel and approximately equally spaced apart therein and in spaced relation to the upper portions of the rim and the central portion, each tube opening through the base for air supply purposes, a stepped plug having a lower portion nested in the aperture of the fuel supplying portion and but partially, in cross section, plugging that aperture, lugs on the plug resting upon the top of the said central portion and a cap of greater cross-sectional area than the central portion aperture for baffling fuel discharge therefrom and between the said lugs, and a manifold having a central hub portion, tubular portions projecting outwardly therefrom and thence downwardly, there being as many tubular portions as there are tube portions and having their downward portions similarly spaced apart, the hub having a central chamber therein opening downwardly and of an area greater than that of the cap, a portion of the latter being disposed in the chamber opening, each tube and cooperating tubular portion having an interfitting connection therebetween, the tubular portions, at their inner adjacent ends having communication with the manifold central chamber and the downward portions solely supporting the manifold upon the tubes.

2. An oil burner as defined by claim 1 wherein each tubular portion is directed inwardly toward and substantially tangentially to the manifold hub portion.

3. An oil burner as defined by claim 2 wherein each tubular portion is, from the interfitting connection to the hub chamber, of substantially progressively decreasing cross-sectional area.

4. An oil burner as defined by claim 3 wherein there is exteriorly provided upon said fuel supplying central portion a plurality of fins, each extending outwardly into the base bowl channel and terminating short of connection with the tubes.
